UNITED STATES PATENT OFFICE.

HENRY TROST, OF COHOES, NEW YORK, ASSIGNOR TO WILLIAM E. BURTON,
OF WATERFORD, NEW YORK.

REFRIGERATOR.

SPECIFICATION forming part of Letters Patent No. 665,814, dated January 8, 1901.

Application filed July 12, 1900. Serial No. 23,358. (No model.)

To all whom it may concern:

Be it known that I, HENRY TROST, a citizen of the United States, residing at Cohoes, in the county of Albany and State of New York, have invented certain new and useful Improvements in Refrigerators; and I do declare the following to be a full, clear, and exact description of the invention, such as will enable others skilled in the art to which it appertains to make and use the same, reference being had to the accompanying drawings, and to the figures of reference marked thereon, which form a part of this specification.

My invention relates to refrigerators, and particularly that type intended for domestic or household use, in which, as usually constructed, there is an ice box or compartment and a provision chamber or chambers through which the cold air from the ice-compartment passes. It is an improvement upon this class of refrigerators that I have designed and which will be described in detail hereinafter, illustrated in the drawings accompanying and forming a part of this specification, and the novel features of which will be set forth in the appended claims.

The essential and novel features of my invention are the provision whereby the food-compartment is placed between two cold-air boxes, one above and the other below, means for cutting off communication between the said food-compartment and lower cold-air box, drainage devices from the upper cold-air box, in which the ice is placed, which prevent any of the water from the melting ice from entering the said food-compartment, and a novel construction of refrigerator frame or casing whereby a swinging door or leaf is provided which effectually conceals the drip-pan beneath the refrigerator when such a pan is used and which may be easily and quickly swung out of the way when it is necessary to remove the said pan for the purpose of emptying it or for the purpose of cleaning beneath the refrigerator.

Other novel features will appear hereinafter and full description thereof made in connection with the drawings, in which—

Figure 1 is an isometrical projection of a refrigerator embodying my invention, the doors of the three compartments being open to show

the interior arrangements. Fig. 2 is a sectional view of the refrigerator in a vertical plane from front to rear. Fig. 3 is a view similar to Fig. 2 in a plane at right angles to the plane of section of Fig. 2. Fig. 4 is a plan view of the bottom of the food-compartment or provision-chamber to show the communicating parts between said compartment and the one below it and the slides or valve-plates which control said openings, the walls of the refrigerator being in section. Fig. 5 is an isometrical projection of the removable rack in the ice-box, upon which the ice or, as shown, the ice pan or receptacle stands and which will be referred to hereinafter; and Figs. 6 and 7 are detail views (enlarged scale) of the door or leaf at the lower front side of the refrigerator, which serves to conceal the drip-pan when turned down.

Referring to the drawings by numerals, like numerals indicating like parts in the several views, 1 indicates the refrigerator, which, as shown, is rectangular in general outline and has an interior lining of zinc or other suitable metal, said refrigerator being divided into three compartments, the upper compartment 2 being separated from the compartment 3 immediately below it by a drip-tray 4, of zinc, said tray 4 being supported on a cross-piece 5, running from front to rear of the refrigerator and having its upturned edges 6 resting flush against the front and back walls of the refrigerator, as clearly shown in Fig. 2.

Referring to Fig. 3, it will be seen that a clear space 7 is left between the edges 6 of the tray 4 and the side walls of the refrigerator, this space 7 being for the purpose of establishing communication between compartments 2 and 3 and allow the cold air to descend freely into the said food-compartment 3. It will be seen that the bottom of the tray 4 is inclined from front to rear (see Fig. 2) and from one side to the other, (see Fig. 3,) so that it will drain to one corner, and at such lower corner is located a drip-pipe 8, to which reference will presently be made. The inclined bottom of said tray 4 would cause the ice-pan 9 to assume a tilted position and a consequent overflow at its lowest corner, if it were placed directly in the inclined tray 4, and in order to insure a level position of

said pan 9 and the proper discharge of the water therefrom to the drip-tray through the drip-holes 10 in the bottom of said pan I provide a pan-supporting rack of peculiar and 5 novel construction. Said rack, as shown in Fig. 5, consists of three slats or bars 11, on which the pan 9 rests when in position, said bars 11 being mortised or otherwise secured to end pieces 12 of unequal heights, so that 10 said rack when placed in the inclined tray 4 will, by reason of the end-supporting pieces 12 of unequal heights, maintain the pan-supporting slats 11 and the pan 9 in a level position. Said end pieces 12 are tapered slightly 15 on their lower edges to compensate for the sidewise slope of the tray 4 and insure a level support for the pan or ice on the slats 11, and their upper edges extend above the top of the bars 11, so as to form flanges 12^a to guide the 20 ice-pan. This compartment 2 is accessible from the front through the door 13, and it will be seen that the ice-pan 9 and its supporting-rack may be readily removed from the tray 4 for the purpose of cleaning the 25 parts. The compartment 3, immediately below and in communication with said ice-compartment 2, is the food-compartment and is preferably closed by a separate door 14, having a double glass front 15, that the interior 30 may be visible at all times, the double glass, with an intervening air-space, giving better insulation from heat and preventing obscuring of the interior by reason of condensed moisture on the glass. In said compartment 35 3 is mounted a series of shelves 16, of any desired number, which are supported at their edges by a series of rods 17, four being shown, which are secured at their upper ends to a cross-shaped frame 18 and at their lower ends 40 to the bottom shelf of the series by means of nuts 19, threaded on the ends of the rods. The shelves are spaced at suitable or desired distances from one another by means of spacing thimbles or sleeves 20, slipped over the 45 rods. The shelves and supporting-frame just described are rotatably mounted within the compartment 3, being made round, as shown, and rotatably supported by trunnions on journal-blocks 21 21^a, secured to the frame 50 18 and the lower shelf, (see Figs. 2 and 3,) said journals taking their bearings in blocks 22 22^a, carried by the tray-supporting cross-bar 5 above and the bottom 23 of compartment 3 below. It will be seen that by the 55 construction described above a rotary series of food-carrying shelves is provided, which are spaced from one another at any desired distances, in which there is no central spindle to obstruct the putting in or taking out 60 the food, &c., the whole construction being light, simple, and so mounted as to be easily rotated.

The food-compartment 3 is separated from the compartment 24 beneath it by means of 65 the floor 25, which is mortised into the front and rear walls of the refrigerator-casing 1 (see Fig. 2) and so upheld, but which has a

clear space 26 between its side edges and the side walls of the refrigerator-casing. (See Fig. 3.) The floor 25 is preferably covered 70 by a zinc plate 27, which fills the entire area of the casing 1, extending over the spaces 26 between floor 25 and the sides of the refrigerator, such extensions of the zinc plate 27 being provided with a series of holes or ports 75 28, as clearly shown in Fig. 4. It will be seen that the compartment 24 will receive the cold air which falls from the ice-box 2 into compartment 3 through said ports 28, and in order to control the supply of cold air to said 80 lower compartment 24 I provide plates 29, pivoted at one end at 30 and being upturned slightly at the other end, so as to form a handle 31. These plates 29 when lying close to the side wall of the refrigerator, as shown at 85 the left in Fig. 4, will completely cover the ports 28 and no air can pass to compartment 24 from compartment 3; but by swinging said plates inward, as shown at the right in Fig. 4, the ports 28 may be partially or wholly uncovered. The compartment 24 may thus be 90 cooled by the air from compartment 3, and, as shown in Figs. 1, 2, and 3, it is also cooled by reason of the fact that in it may be placed a drip-pan or waste-water receptacle 32, the 95 drip-pipe 8, hereinbefore referred to, passing from the drip-tray 4 down through compartment 3 at one corner thereof, (see Figs. 1 and 3,) enters compartment 24, and delivers into the drip-pan 32. The water received from 100 the drip-tray 4 has a cooling effect on compartment 24, and it may be used for a storage-compartment, if desired, a door 33 closing the 105 said compartment 24 at its front. The drip-pipe 8 may pass through the bottom of the 110 refrigerator, if desired, and deliver to a drip-pan placed beneath said refrigerator 1, and in order to furnish means whereby a drip-pan may be readily placed or removed from under the refrigerator I have provided the following construction:

At the bottom of the refrigerator-casing and at the front thereof is a leaf or door 33^a, pivoted at its ends near its upper edge in blocks 34, secured to the bottom of the refrigerator. 115 Said pivoted door 33^a bears against stops 35, formed on the blocks where hanging in its vertical position, (see full lines, Figs. 6 and 7,) but may be swung outwardly and upwardly to a horizontal position and pushed back to 120 the position shown in dotted lines, Fig. 6, ways 36 being formed in the blocks 34 to receive the ends of said door 33^a when thrown to its horizontal position, the bottom of the refrigerator being channeled at 37 to allow 125 the door to swing on its pivot, and yet permit a comparatively close joint between said refrigerator-bottom and the top of the swinging door 33^a, as will be seen in Figs. 6 and 7. This permits the construction of a refrigerator-casing in which the ornamental effect of 130 moldings, &c., may be carried out on all four sides of the refrigerator, as seen in Fig. 1, and the necessity of leaving a gaping open-

ing at the bottom in the front of the refrigerator to admit the drip-pan is obviated, while at the same time, by means of the pivoted door above described, access to the drip-pan 5 for removal of the same or for the purpose of cleaning beneath the refrigerator is easy.

Having described my invention and set forth its merits, what I claim is--

1. The refrigerator comprising a central food-compartment, a top ice-compartment and a bottom storage-compartment, the central compartment being separated from the top compartment by a partition, the ends of which are set back from the sides of the refrigerator-body for the passage of air-currents between the two compartments, and separated from the bottom compartment by a partition which is formed with ports at opposite ends for communication with the bottom compartment, rotatable shelves in the central compartment, a separate door to each compartment, and independently hand operated valves for controlling the ports in the lower partition so as to establish or cut off communication as may be desired between the central food-compartment and bottom storage-compartment when the doors are closed, substantially as described.

2. A refrigerator having an ice-compartment, a drip-tray in said compartment the bottom of which is inclined so as to drain to one corner thereof, a drip-pipe at said drainage-corner, a food-compartment below said ice-compartment and communicating therewith, a series of rotary shelves in said food-compartment, a cooling and storage compartment below said food-compartment and connected therewith by ports, into which said drip-pipe delivers, pivoted plates to control the said ports and a waste-water receptacle in the bottom storage-compartment at the delivery end of the drip-pipe, substantially as described.

3. In a refrigerator having an ice-compartment, the combination with a drip-tray having its bottom inclined in two directions and provided with a drip-pipe at its lowest point, of a leveling pan-supporting rack having end supports of unequal heights and tapered lower 50 edges in said drip-tray, an ice-pan having a

perforated bottom on said rack, said refrigerator having a food-compartment below said ice-compartment and in communication therewith, a shelf-supporting frame in said food-compartment comprising a series of rods 55 on which the shelves are mounted, spacing-sleeves on said rods to separate and hold said shelves in position, trunnions at either end of said frames, bearings for said trunnions, a storage and cooling compartment below said 60 food-compartment into which said drip-pipe delivers, ports connecting said food and storage compartments, and plates pivoted at one end in said food-compartment to cover said ports when desired, substantially as described. 65

4. In a refrigerator, the combination with the cross-bar 5, of the inclined drip-tray 4 mounted thereon, said tray dividing the ice-compartment 2, from the food-compartment 3, with the exception of cold-air spaces 7 at 70 either side of said tray, a leveling ice-rack mounted in said tray, a bearing-block 22 on the under side of said cross-bar 5, a shelf-supporting frame having a trunnion 21 mounted in said bearing-block 22, a floor 25 dividing 75 said compartment 3 from a cooling and storage compartment 24 in the bottom of the refrigerator, ports 28 connecting said compartments, port-controlling plates 29, a bearing-plate 22^a fixed to said floor 25, and a trunnion 80 21^a on said shelf-supporting frame; whereby said frame and shelves are rotatably connected within said compartment, substantially as described.

5. A shelf-supporting frame for refrigerators comprising two end heads provided with trunnions, of a series of circumferentially-placed rods secured near the peripheries of said heads, a series of shelves mounted on said rods and spacing thimbles or sleeves on 90 said rods between the said shelves to hold them in position on said rods said thimbles extending from one shelf to another, substantially as described.

In testimony whereof I affix my signature 95 in presence of two witnesses.
